H. HOLLAND.
STOCK SALTING AND FEEDING DEVICE.
APPLICATION FILED APR. 11, 1919.

Patented Dec. 9, 1919.

UNITED STATES PATENT OFFICE.

HOMER HOLLAND, OF CENTER, COLORADO.

STOCK SALTING AND FEEDING DEVICE.

1,324,593.

Specification of Letters Patent.

Patented Dec. 9, 1919.

Application filed April 11, 1919. Serial No. 289,241.

To all whom it may concern:

Be it known that I, HOMER HOLLAND, a citizen of the United States, residing at Center, in the county of Saguache and State 5 of Colorado, have invented certain new and useful Improvements in Stock Salting and Feeding Devices, of which the following is a specification.

The present invention comprehends generally improvements in that class of inventions known as animal husbandry and more particularly relates to a stock salting and feeding device.

This invention has for its primary aim 15 and object to provide a device of the above mentioned character designed to be readily maintained in a set-up position for receiving food and salt for stock such as sheep, the component parts being novel in construction 20 so as to permit of the collapsing thereof in order that the device will occupy only a minimum amount of space when not in use or when being shipped.

As an additional and equally important 25 object this invention contemplates the provision of a device of the above mentioned character wherein the support is of novel construction and has associated therewith flexible trough and flexible covering flaps 30 for the troughs to prevent rain from entering the troughs, while coacting means is mounted on the flaps and on the supports for releasably holding the flaps in a raised position so that the flaps will in effect form 35 guards for preventing wasting of food and salt while the sheep are feeding.

It is a more specific object of this invention to provide a device of the above mentioned character wherein the troughs are of 40 a peculiar and novel construction and are so mounted on the supports that the device cannot be easily overturned while the sheep are feeding.

Among the other aims and objects of this 45 invention may be recited the provision of a device of the above mentioned character wherein the number of parts are comparatively few, the construction simple, the cost of production low and the efficiency high.

50 Other objects, as well as the nature, characteristic features and scope of this invention will be more readily apparent from the following description taken in connection with the accompanying drawings and pointed out in the claims, forming a part of this specification.

The invention is clearly illustrated in the accompanying drawings, in which:—

Figure 1 is a top plan view of the improved feeding and salting device, 60

Fig. 2 is a vertical transverse sectional view thereof, and

Fig. 3 is an enlarged sectional detail through one of the troughs.

Similar characters of reference are employed in all of the above described views, to indicate corresponding parts.

Referring now, more particularly, to the accompanying drawings there is provided an improved support in the present instance 70 consisting of a plurality preferably four supporting legs 1, the inner adjacent ends of which carry connecting elements 2 which are pivotally arranged about the adjacent spaced seat portions of a substantially square 75 loop 3. In this connection it is to be observed that the connecting elements are formed desirably from pieces of strap iron which are bent to a U-shaped configuration and are fastened to the ends of the legs by 80 fasteners 4 so that their intermediate portions are spaced from the inner ends of the legs which form substantial hinges 5 while the straight portions of the loop 3 constitute in effect a pintle. 85

In order to limit the outward movement of the legs and maintain them in a properly supported position, suitable flexible retainers in the form of cables are employed, the free ends of the cables being connected to 90 each other while both of the cables are arranged about the legs and the attaching devices 7 which are carried by the legs so as to be held in proper position, the flexible retainers 6 assuming a substantially rectangular or square form when the legs are extended, the spreading movement of the legs being limited when the side portions of the cables become taut and it is apparent upon reference to the drawings that the side portions of the cables 6 are arranged in parallel 95 relation with each other.

In order to maintain the supporting legs in an extended position, there has been provided a relatively heavy weight 8 which is 105 suspended from the loop 3 by means of a flexible element such as a cable 9.

With a view toward providing the improved means for receiving salt and food, pieces of flexible material such as canvas are 110 employed, the lower edges being hemmed to form casements 10 which are arranged

about the lower straight portion of the lower cable or retainer 6 while the medial portions are hemmed to form other transverse casements 11 which are arranged about the adjacent straight portions of the upper retainer or cable 6, the lower portion of each piece of the material being allowed to hang or drape between the two cables as shown to form a flexible trough 12 while the upper portion of each piece of flexible material constitutes a flexible covering flap 13 for the adjacent trough. The material forming the trough may be composed of a single piece or else the end edges of the lower portions which form the trough proper may be stitched together so as to in effect provide a continuous trough which is positioned to suspend within the support. The upper portions which form the flaps extend beyond the supporting legs and have their end portions folded under when raised as shown in Fig. 2. It will thus be seen that when it is raining these flaps may be lowered to cover the trough and protect the food and salt placed therein, the extended end portions of the flaps covering the end portions of the trough adjacent the supporting legs. With a view toward providing the improved coacting means for releasably retaining the flaps in a raised position so that they will form guards to prevent the wasting of food and salt while the sheep are feeding, eyes 14 are connected to the free edges of the flaps near the end or side edges thereof while carried by the legs are hooks 15 with which are releasably engaged the eyes 14 which are positioned at the ends of adjacent flaps 13, the arrangement being clearly indicated in Fig. 1.

It is believed in view of the foregoing description that a further detailed description of the operation of the invention is entirely unnecessary. Likewise, it is believed that the advantages of the invention will be readily apparent. However, in this connection it is to be observed that on account of the slant of the supporting legs and the fact that the troughs are flexible the device cannot be easily upset by sheep or other stock rubbing thereagainst. Attention is also particularly directed to the fact that the flaps when in a raised position form guards by directing all salt or food which is dropped from the mouth of the sheep or

stock back into the trough and in addition of course serve as a means for effectively covering the trough and protecting the food in rainy weather.

Still further embodiments of the invention than those herein especially defined may be resorted to as conditions or preference may dictate, as may be in keeping with the hereto appended claims.

Having thus fully described the invention, what is claimed as new and desired to be secured by Letters Patent, is:—

1. A device of the character described including a plurality of supporting legs the adjacent upper ends of which are connected for independent vertical movement, spaced flexible retainers arranged about and connected with the legs for limiting spreading movement of the legs, and flexible troughs connected with the retainers.

2. A device of the character described including a plurality of supporting legs, a loop, connecting elements carried by the upper ends of the legs and pivotally connected with the adjacent portions of the loop, spaced flexible retainers arranged about the legs for limiting spreading movement thereof, flexible troughs connected with the retainers and independent flexible flaps for each of the troughs designed to removably cover the troughs and to provide guards for the troughs.

3. A device of the character described including a plurality of supporting legs, a square loop, connecting elements carried by the adjacent upper ends of the legs and pivotally arranged about the adjacent straight portions of the loop, a pair of flexible retainers arranged about and connected with the legs and arranged in spaced relation with each other and designed to limit spreading movement of the legs, flexible troughs connected with the retainers and arranged between adjacent legs, independent flexible flaps for each of the troughs for closing the troughs when desired, and co-operative fastening means carried by the flaps and the legs for releasably holding the flaps in a raised position so that they will provide guards for the troughs while sheep or other stock are feeding therefrom.

In testimony whereof, I affix my signature hereto.

HOMER HOLLAND.
